A. F. SHORE

SPRING SUPPORT FOR VEHICLES

Filed April 11, 1921

Fig. 1 Fig. 2 Fig. 3 Fig. 4 Fig. 5

Albert F. Shore, INVENTOR
BY
George Hoffman, ATTORNEY

UNITED STATES PATENT OFFICE.

ALBERT F. SHORE, OF NEW YORK, N. Y.

SPRING SUPPORT FOR VEHICLES.

Application filed April 11, 1921. Serial No. 460,193.

To all whom it may concern:

Be it known that I, ALBERT F. SHORE, a citizen of the United States, residing at New York, in the county of New York and State of New York, have invented certain new and useful Improvements in Spring Supports for Vehicles, of which the following is a full, clear, and exact specification.

This invention relates to spring supports for vehicles such as automobiles, and its principal object is to provide means for counteracting or nullifying the objectionable end vibrations or transversely centered oscillations set up in the suspended body. The principle utilized to accomplish this end is the one of gyratory resistance, which is set up by imparting to the said suspended body a certain amount of rolling motion or oscillations having an axis or center of gravity disposed longitudinally of the body, or, as herein termed, longitudinally centered oscillations.

In a co-pending application, filed by me on December 11, 1920, Serial No. 429,841, I sought to attain this result by the use of a semi-elastic subframe carrying springs pivotally mounted approximately midway between the front and rear axles, which springs support the middle part of the weight of the chassis and upper structure, while adjacent to the front and rear axles the usual but now comparatively lighter springs are used. It has been found that the desired parallel and more vertically disposed vibrations of less amplitude can thus be obtained. However, there appears to be a desirability for a still greater ease of riding, as by combining with the said more parallel and vertically disposed vibrations, oscillations gravitationally centered longitudinally of the body. These are not objectionable to the passenger, as are the end vibrations or transversely gravitationally centered oscillations, as can be demonstrated by going diagonally over a rail or ditch on the road, which breaks up a severe jolt partially by causing the aforesaid rolling motion or longitudinally centered oscillations of the body. These longitudinally centered oscillations also tend to nullify transversely centered oscillations, due to a certain amount of gyration that is set up in the suspended body. In other words, it develops gyratory resistance to the objectionable end bounces or transversely centered oscillations. This result is attained, accord-

ing to my present invention, by the provision of springs that are of unequal strength, resiliency, or periods of vibration in any predetermined transverse plane of the vehicle; in other words, by making a certain spring on one side of the vehicle comparatively stiff or strong and the corresponding spring on the other side of the vehicle comparatively weak or more elastic and having a longer period of vibration.

Several embodiments of my invention have been shown in the accompanying drawings, in which

Figure 1 shows in plan view a chassis of ordinary construction having springs extending lengthwise of the frame;

Figs. 2 and 3 show springs of my new type, as they would be used in a construction having transverse springs; and

Figs. 4 and 5 show, in side and front elevation respectively, my invention as applied to a spring suspension system as illustrated in my co-pending application above referred to.

Referring first to Fig. 1, A represents the conventional vehicle frame supported on the front axle B and rear axle C by means of springs D, D', E, E', extending lengthwise of the frame. As will appear clearly from this view, the springs D, D' are of unequal width and therefore also of unequal strength, the spring D being narrower and somewhat weaker than the adopted standard, while the spring D' is wider and somewhat stronger than the adopted standard. With the rear springs, both may be of equal strength, or the front arrangement is reversed, the spring E (located on the same vehicle side as the weaker spring D) being wider and stronger, while the spring E' (corresponding in location to the stronger front spring D') is the weaker one of the two rear springs.

If the vehicle is provided with transverse springs, the desired effect is attained by constructing each spring in itself of unequal strength on its two supporting ends. Such a construction of springs has been illustrated in Figs. 2 and 3, the springs of Fig. 2 corresponding to and functioning in a manner similar to the front springs D, D' of Fig. 1, and those of Fig. 3 to the rear springs E, E' of Fig. 1. It will be seen that the individual leaves of the spring F in Fig. 2 project more to one side from the center line than to the other, so that

this spring consists of relatively weak elements f and relatively strong elements f' . In Fig. 3, the arrangement is reversed, the spring G consisting of relatively strong elements g (corresponding in location to the weak elements f) and of relatively weak elements g' (corresponding in location to the strong elements f' of the spring F). In this construction, the position of the relatively weak elements f in Fig. 2 and the position of the relatively weak elements g' in Fig. 3, before the engine is placed in the forward end of the chassis, is indicated in dotted lines, and the position of the same elements, after the engine is placed in the forward end of the chassis, is indicated in full lines. It is, therefore, understood that, as regards the fixed weight of the forward part of the suspended body which carries the motor and driving mechanism, the springs are so proportioned that normally the suspended body will always be properly balanced and rest without a tilt or angle. For example, the strong spring will have a flexure of one inch per five hundred pounds, while the weaker spring will have a flexure of two inches per five hundred pounds. Let us assume that the motor weighs five hundred pounds. Before placing the motor in position, it would, therefore, be necessary to have the frame one inch higher on the weak spring side than on the strong spring side, and as the weight of the motor is added, there will be a sag of one inch on the strong spring side and a sag of two inches on the weak spring side. Inasmuch as the latter side had been an inch higher than the former side, it is evident that the effect of the weight of the motor will be to properly balance the vehicle body and hence prevent sagging above the weaker springs or spring elements under full load. With this accomplished, it will also be evident that when a shock is communicated to the wheels of the vehicle of equal force on each wheel, the effect will result in uniform responses, as hereinafter more fully explained.

Figs. 4 and 5 illustrate my invention as applied to a spring suspension system shown in and forming the subject of my application above referred to, and detailed description of these views is not thought necessary. A' represents a semi-elastic sub-frame carrying the chassis frame A'' by means of fulcrum springs H arranged approximately midway between the front and rear axles B', C' , and also by means of comparatively light springs I, J . There are two fulcrum springs H , one adjacent to each longitudinal frame member, and it is to be understood that these fulcrum springs may be constructed like the springs D, D' in Fig. 1; that is to say, the spring on one side may be stronger than the spring on the other

side. Likewise, the comparatively light springs adjacent to the axles may be constructed alternately strong or weak, or with strong or weak elements. I may, of course, construct one or the other sets of springs of even strength, and the remaining set or sets of unequal strength, but always taking into consideration that the vehicle body must be properly balanced, so as to prevent sagging above the weaker springs or spring portions under load. 75

When a vehicle equipped with my new spring arrangement strikes an obstruction in the road, as a rail, with both front wheels simultaneously, the effect will be to throw the body harder on the side having the stronger spring, so that it will tend to move about its center of gravity, developing an axis which is disposed longitudinally of the vehicle. The throw thus started is further accelerated after said object has been struck and the wheels again fall to the normal level of the road, for, in this instance, the said fall of the suspended body is resisted less on the side having the weaker spring than on that having the stronger spring. 80

As the vehicle passes on, the rear wheels strike the same obstruction, and even though there may be no provision of a strong and weak spring, but a spring set of equal power as has hitherto been used, the rolling motion imparted to the body by the front wheels will materially mitigate the intensity of the said rear wheel shock and also serves to arrest the hitherto objectionable end bounces and the series of transversely centered oscillations which follow. When, however, the rear springs are also made relatively weak and strong, but with their powers reversed relative to those of the front wheels, a reverse rolling action takes place. To thus obtain greater ease of riding, it can here be seen that I not only provide a confusion of vibrations but also develop a certain amount of gyroscopic resistance which further serves to arrest and mitigate those vibrations which are most objectionable to the passenger. 100

I claim:

1. In a spring support for vehicles, relatively strong spring means located adjacent to one axle at one side thereof, and spring means relatively weak at all times on the other side. 115

2. In a spring support for vehicles, relatively strong spring means located adjacent to one axle at one side thereof, and spring means relatively weak at all times on the other side of said vehicle, the arrangement of relatively strong and relatively weak springs being reversed adjacent to the other axle. 120

3. In a spring support for vehicles, relatively strong and relatively weak spring 125

means, said relatively strong spring means being in alternation with said relatively weak spring means on the same side of the vehicle.

- 5 4. In a spring support for vehicles, springs extending transversely of the vehicle adjacent to the vehicle axles, one of said springs comprising relatively strong elements on one side of the central longitudinal axis of the vehicle, and elements relatively weak at all times on the other side of said plane, the arrangement of relatively strong and relatively weak spring elements being reversed in the other spring.
- 10 5. In a spring suspension for vehicles, relatively stiff spring means and spring means relatively elastic at all times arranged,
- 15

respectively, on opposite sides of the vehicle.

6. In a spring support for vehicles, relatively strong spring means at one side thereof and spring means relatively weak at all times on the opposite side.

7. A spring suspension for vehicles having greater resiliency at one side of the vehicle than at the opposite side thereof, for the purpose specified.

8. In a vehicle, the combination with a wheel axle and chassis frame, of a spring suspension for the frame from the axle said suspension having unequal resiliency on opposite sides of the longitudinal axis of the vehicle.

In testimony whereof, I affix my signature.

ALBERT F. SHORE.
